**METHOD AND APPARATUS FOR PRODUCING
AND APPLYING BAG HANDLES**Arno Finke, Muhlenweg 5, and Siegfried Kosterlitzky,
Hohne 413, both of Lengerich, Germany

Filed May 14, 1959, Ser. No. 813,302

Claims priority, application Germany May 14, 1958
13 Claims. (Cl. 93—8)

The present invention relates to bags from paper and the like material. More in particular, the present invention relates to a new and useful method for producing and applying to bags handles, and an apparatus for producing and applying to bags handles therefor.

It is known to provide handles for bags, particularly paper bags, which are U-shaped and have a grip portion which is folded both downwardly and inwardly, with respect to the bag proper, by one single fold.

There are also known in the art machines for producing and applying handles of a less advantageous type than the one just referred to. These machines are, however, not susceptible to producing and applying to the bags handles which have a downwardly and inwardly folded grip portion.

Furthermore, the known machines are not susceptible to producing and applying to bags handles having a double folded grip portion. It has been found, however, that, advantageous as the above mentioned handle with the single although downwardly and inwardly effected fold may be as compared with other known handles, it still is susceptible to further improvement, as far as its stability and sturdiness and its capability of carrying great loads as well as its adjustability to the size of the carrying person's hand are concerned.

In addition, the known machines are unsatisfactory in that their operating speed is comparatively low.

It is an object of the present invention to provide a method and an apparatus for producing and applying to bags handles having a grip portion which is folded downwardly and inwardly with respect to the bag proper.

It is another object of the present invention to provide a method and an apparatus for producing and applying to bags handles which are sturdier and capable of carrying a greater load and more adjustable to the size of the carrying person's hand than known handles.

It is further an object of the present invention to provide a method and an apparatus for producing and applying to bags handles having a grip portion which is double folded downwardly and inwardly, with respect to the bag proper.

It is still another object of the present invention to provide a method and an apparatus for producing and applying to bags handles which operate faster and more accurately than known apparatus.

These objects as well as further objects and advantages which will become apparent as the description proceeds are achieved by the method and the apparatus of the present invention, according to which the strip of material from which the handle is to be produced, is first double folded in its grip portion, whereupon the end portions are folded so as to form an angle with the grip portion contrary to the direction in which the strip is conveyed; the strips are then turned over and applied with the side that is now the upper side to the bags.

The invention will be better understood upon the following detailed description of the accompanying drawings, wherein,

FIGURES 1 through 11 are schematic views illustrating, in reference, the various steps comprised by the method of the present invention;

FIGURE 31 is a largely schematic top view of the entire machine, and more particularly, the preferred embodiment illustrated in FIGURES 15 through 30c;

FIGURE 32 is a somewhat schematic side elevational view of another embodiment of the machine of the invention, and shows the upper portion of the handle forming unit;

FIGURE 33 is a somewhat schematic top view of the unit shown in FIGURE 32;

FIGURE 34 is a somewhat schematic side view of part of the embodiment shown in FIGURES 32 and 33;

FIGURE 35 is a front view of the part of the unit shown in FIGURE 34.

The method of the invention is as follows:

A strip of paper or the like material is pulled off a feed roll. Preferably crepe paper is used for producing

the bag handle. The strip of material has twice the width of the width of the handle produced therefrom or its portions to be glued to the bag. If crepe paper is used, it will be found of advantage to smooth the surface of the paper at the locations which are to be attached by gluing, as at 3. Thereafter, glue is applied to the side portions of the paper strip as at 4 and 5, and these portions are then folded inwardly towards the middle of the strip, thereby obtaining a strip of material 6, having twice the thickness and half the width of the original paper strip. The strip 6 is then provided with grooves 7 through 10, that is angular grooves 7 and 8 upon the visible side of the side strips now folded over the center of the strip and a short transverse groove 9 and 10 reaching from the top of the angular grooves 7 and 8 in the strip center towards the edge of the strip on the invisible side of the strip. These grooves are provided for the corner foldings which will be referred to presently.

The strip of material 6 is then cut into a plurality of individual portions 11, each having the required length for further producing the bag handle.

The strip which heretofore had travelled in the direction of arrow 1a is now moved in the directions of arrows 1b, its motion thus being changed by an angle of 90 degrees.

Thereafter the strips are double-folded in their grip portions 14, as shown in FIGURE 3. They are then turned by an angle of 90 degrees about their longitudinal axis and contrary to the directions of arrows 1b, as shown in FIGURE 4, whereupon the respective end portions 15 and 16 are folded backwardly and the corner foldings 17 and 18 are effected, thus obtaining a U-shaped configuration (see FIGURES 5 and 6). Thereafter, the handles are again turned by 90 degrees as shown in FIGURE 7, and then again by 90 degrees as shown in FIGURE 8, so that the under-side is now turned upwardly. The end portions are then provided with a layer of glue as at 19 and 20 for attaching the handles to the bags. Thereafter, the handles can be attached to the bags which is preferably done by again turning the handle by a total of 180 degrees as illustrated in FIGURES 9 and 10 and bringing the handles and the bags together and then pressing the glued portions 19 and 20 upon the bag (see FIGURE 11).

The Basic Embodiment of the Machine

According to a basic embodiment of the apparatus for practising the method of the invention there are provided means for preparing the strip of paper or the like material, and for cutting it into portions of the requisite lengths, folding means, corner folding means, means for turning and applying the handle to the bag, and transfer means between the latter and the strip-preparing-and-cutting means.

The apparatus is adapted for simultaneously producing two handles for each bag to be applied to either side of the bag. Consequently, the apparatus is provided with two means for forming the handles and applying the same to the bag which are symmetrically disposed with respect to the bag-conveying means, the latter being, for example, arranged horizontally in between the upper and the lower handle-forming and applying means, each applying simultaneously a handle on the upper and the lower sides of the bags, respectively.

The upper and the lower handle-forming and applying means are substantially alike and, consequently, it suffices to describe only one of these symmetrically disposed, substantially identical means.

The Handle Strip Producing Mechanism of the Basic Embodiment

The basic embodiment of the machine of the invention comprises the following units and elements, always in duplicate so as to produce two handles simultaneously, but of which only one is described for the sake of conciseness.

The strip of material is stored on a feed roll 24. There is provided a pair of advancing rolls 21, 22, driven by a motor (not shown) at a predetermined, constant speed. Between the advancing rolls 21, 22 and the feed roll 24, 5 the machine has a pair of smoothening rolls 25, 26, whereof roll 25 has a segment-shaped cross-section, and a glue applying unit with the glue vessel 27, the roll 28, partly projecting into the glue vessel, and thereabove the roll 29. A longitudinal folding flap 30 and a further 10 pair of rolls 31, 32, are disposed between the glue applying unit 27, 28, 29, and the advancing rolls 21, 22. The roll 31 has two projections 31a, 31b, whereas the counter roll 32 has two corresponding recesses 32a, 32b, adapted to receive the projections 31a, 31b, in the course of rotation of the two drums.

On the opposite side of the advancing rolls 21, 22, the machine has the cutting unit with rotating body 33 bearing the cutting blade 34 which acts together with the stationary blade 34a and, thereafter, a further pair of conveying rolls 35, 36, and a third pair of conveying rolls 37, 38. The roll 37 has a segment-shaped and somewhat larger cross-section than the other conveying rolls. The rolls 37, 38, have a greater circumferential speed than the first and second pair of conveying rolls.

25 Next, there are provided four pairs of conveying rolls 39, 40; 41, 42; 43, 44; and 45, 46, all having the same circumferential speed as the pair 37, 38. The upper rolls can be lifted from the lower rolls of the four pairs of conveying rolls by the side bars 39a, 41a, 43a, 45a. 30 Next to the four pairs of rolls, a reciprocable bar 47 is adapted for arresting the movement of the strip of material (23).

The Handle Strip Transfer Mechanism of the Basic Embodiment

35 The machine further has a transfer unit comprising a displaceable lever 51 bearing three needles 48, 49, 50 (see FIGURE 13). The reciprocating lever 51 is fulcrumed as at 55 on a reciprocating lever 56 which, in turn, is 40 mounted on the shaft of a curved disc 52. The lever 51 is hingedly connected to a lever 54 also fulcrumed as at 55 and bearing at its opposite end a feeling roll 53 scanning the curved disc 52.

The Handle Forming and Applying Mechanism of the Basic Embodiment

45 Next to the three needles, there is disposed a cylinder 58 rotating in the direction of arrow 63 bearing at its periphery opposite to each other the grippers 59 and 60, and adjacent thereto, the folding clamps 61 and 62, respectively. Close to the cylinder 58 there is mounted the folding knife 64 rotating in the circle 64a in the direction of arrow 64b. The folding knife 64 cooperates with the folding clamps 61, 62 in a manner described further below. Adjacent to cylinder 58 there are further 50 provided pressure rolls 67 and 68, and the oblique bars 65, 66, as well as the tongues 69 and 70. Guide blades 71, 72, are positioned adjacent to the portion of cylinder 58 opposite to the folding knife 64. Next thereto and also adjacent to cylinder 58, a cylinder 73 rotates in an opposite sense with respect to cylinder 58 and bears grippers 74. The cylinder 73 also has a plurality of suction nozzles 75. Further glue-applying means next to cylinder 73 comprise the rolls 79, 78, 77, the latter partly projecting into a glue vessel 76 and with the roll 79 being positioned adjacent to cylinder 73.

The Bag Conveying Mechanism of the Basic Embodiment

The machine also has bag conveying means with an 70 upper pair of conveyor belts 82 running on rolls 90, 91, and tightened by pressure rolls 92, 93, and a lower pair of conveyor belts 83 running on rolls 94, 95, and tightened by pressure rolls 96, 97, 98. The belts pass between the cylinders 73 and 80. At one end of this conveyor 75 system there is another conveyor system for passing the

bags to the aforementioned conveyor belts, and comprising the conveyor belt 84 running on rolls 84a, 84b, and bearing a plurality of transverse push bars 85 arranged at predetermined distances from each other. Between the conveyor belts 82, 83, on the one hand, and the conveyor belt 84, on the other hand, there are disposed opposite to each other two advancing rolls 86 and 87, the roll 86 having a segment-shaped cross-section. These two rolls revolve at substantially the same circumferential speed as the rolls 90, 91, and 94, 95, for the conveyor belts 82 and 83, respectively, whereas the circumferential speed of the rolls 84a and 84b for the conveyor belt 84 is somewhat slower.

At the opposite end of the conveyor belts 82, 83, there is arranged a rack 81 for receiving the bags conveyed by the belts 82, 83.

The Bast Containing Handle Embodiment of the Machine

According to another embodiment of the present invention shown in FIGURES 32 and 33, the apparatus comprises means for preparing the strip, means for cutting the strips so as to obtain strip portions of the required length for a handle, handle forming means, and means for applying the handle to the bags, conveying means for conveying the bags, and transfer means for transferring the strips from the strip-preparing-and-cutting-means to the handle-forming-and-applying-means.

The Handle Strip Producing Mechanism of the Bast Containing Handle Embodiment

The machine has a roll 123 on which there is stored a strip of material for producing the bag handle, e.g. paper, and a second feed roll 125 on which there is coiled a supply of bast, also used for producing the bag handle as explained further below. Two guide rods 126 and 127 are associated with the feed roll 123; and are equipped with lateral guide rings 128, 129 (see FIGURE 33). Between the rods 126, 127, there is disposed an advancing roll 130.

The glue applying means of the machine comprise the glue vessel 134, and, partly projecting into the glue vessel, a central glue-applying disc 135 and before as well as behind the same, glue-applying discs 137 and 138, respectively, the latter having partly interrupted portions as at 136. A counter roll 131 revolves oppositely with respect to the sense of rotation of the glue-applying discs 135, 137, 138.

A guide rod 140 provided with adjustable lateral guide rings 141 and 142 is associated with the bast feed roll 125 and disposed between the latter and the counter roll 131 of the glue-applying means for the strip of material, e.g. the paper strip 122.

Next to the glue-applying means the machine is equipped with cutting means 143 composed of the fixed knife 144 mounted on the stationary body 144a, and, arranged thereabove, two rotating knives 146 and 147 on the rotary body 145. As shown in FIGURE 33 of the drawings, the rotating knives 146 and 147 each have a recess portion 148 disposed in the central edge portion of the knife blades.

Next to the cutting unit 143, the machine has another guide rod 151 provided with two lateral, adjustable guide rings 152, 153. Thereafter, the folding device 154 is provided, with the shoe 155 having the same width as the bast strip, the rotating segment discs 156, 157, disposed at either side of the shoe 155, a first folding bar 160 and a second folding bar 161.

The Handle Strip Transfer, Forming and Applying Mechanism of the Bast Containing Handle Embodiment

The remaining elements of the machine are identical to those of the basic embodiment of the apparatus of the invention, as described further above.

However, instead of the folding knife 64, this embodiment of the apparatus according to the invention is equipped with two grooving tools 167 and 168 mounted

on a driving shaft 169, and the cylinder 58 has two corresponding diagonal grooves 172 and 173 into which the grooving tools 167 and 168 are adapted to reach.

Furthermore, this embodiment has fixed plates 174, 175, close to the portion of cylinder 58 having the grooves 172, 173. These plates have enlarged end portions 176, 177, respectively. Between the plates there are provided interior guide plates 178 and 179 (see FIGURES 34 and 35 of the drawings).

In addition, the cylinder 58 has suction nozzles 181 and 182 in its wall, and associated with a resilient plate 180 for pressing the strip of material against the suction nozzles.

Operation of the Basic Embodiment of the Machine

The strip of material, for example and preferably, a strip of crepe paper 23, is pulled off a feed roll 24 by means of the pair of rolls 21, 22. The strip of crepe paper passes between the smoothening rolls 25, 26 the roll 25 being in the shape of a segment, thereby smoothening only predetermined sections, as 3. From there the strip passes between the rolls 28 and 29 of the glue applying unit and glue is applied to the side portions of the paper strip as at 4 and 5. Then the strip is drawn through the longitudinal folding flap device 30, where the sides of the strip which have the glue 4 and 5 applied thereto are folded inwardly towards the middle of the strip, thereby obtaining a strip of material 6, having twice the thickness and half the width of the original paper strip. The thus formed strip is then guided underneath the creasing roll 31 with the projections 31a and 31b and over the roll 32, having corresponding recesses 32a and 32b. Thereby the strip is provided with the angular grooves 7 and 8 upon its upper side and the short transverse grooves 9 and 10 on its under side, reaching from the top of the angular grooves in the strip center towards the edge of the doubled strip. From the creasing unit the strip passes between the pull and forwarding rolls 21, 22, which advance the strip through the cutting unit 33, 34, 34a towards the conveying rolls 35, 36. Each time the revolving knife 34 of the knifeholder 33 reaches the lower stationary knife 34a (as shown in FIGURE 12).

The transfer means comprising the three needles 48, 49 and 50 mounted on displaceable lever 51 (see FIGURE 13) now pierce the strip of material momentarily at rest. The reciprocating movement of the lever 51 for introducing the needles into the strip of material and reducing the same therefrom is effected about the fulcrum 55, and is controlled by a curved disc 52 via the feeling roll 53 and the further lever 54. The fulcrum 55 is disposed on a third lever 56 which latter performs a reciprocating movement in the direction of the double-headed arrow 57, via a further lever not shown. By the reciprocating movement of the needles the strip of material is transferred to the cylinder 58. Here it is grasped by grippers 59 and 60, respectively. The center of the strip is now disposed over the folding clamps 61 and 62, respectively. The cylinder rotates in the direction of the arrow 63 and the folding clamps rotate therewith until they meet with the folding knife 64, rotating in the direction of arrow 64a in the circle 64a, the knife thus rotating in the opposite direction with respect to folding clamps 61, 62. As soon as one of the folding clamps encounters the folding knife 64 the grip portion 14 of the strips between the grooves 7, 9, and 8, 10 (FIGURE 1) is double-folded as illustrated in FIGURE 3. In the meantime, the grippers 59 and 60 have released the strip.

The portions 15 and 16 (see FIGURE 14) laterally project from the cylinder 58 and are folded by the oblique bars 65 and 66 about the corner folds 17 and 18. The corner portions which come to rest upon one another are firmly pressed against each other by the pressure rolls 67 and 68. The exact positioning of the folds is guaranteed by tongues 69 and 70 which come to rest

against the transverse grooves 9 and 10 (FIGURE 1) of the strip of material illustrated by the dash-dotted lines in FIGURE 14.

The guide blades 71 and 72 receive the end pieces 15, 16 of the handles and bring the same into the necessary position when the strip is transferred from the cylinder 58 to the cylinder 73. The central portion 14 of the handle is gripped by the grippers 74 and the end portions 15, 16 are firmly held against the cylinder by the suction nozzles 75.

After having rotated with the first cylinder 58 and having been transferred to the second cylinder 73, the handle has been turned due to this transfer to the cylinder 73 rotating oppositely to the rotation of cylinder 58. The lower side of the handle is now accessible and can thus be glued to the bag with its glued end portion, while having an inwardly folded grip portion. If the handle would not be transferred in this manner from the cylinder 58 to the cylinder 73, the grip portion of the handle would be outwardly folded with respect to the finished bag.

The accessible side of the end pieces 15 and 16 of the handle is now advanced to the glue-applying means 76, 77, 78, 79. It is thereby provided with the glued portions 19 and 20, as shown in FIGURE 8. Thereafter, it continues to rotate with cylinder 73 down to the lowermost end of the latter where the handle encounters the bags. The bags pass between the cylinder 73, supplying the upper handle and the cylinder 80 supplying the under handle. The bags move with the same speed as the handles and are advanced in the predetermined intervals, so that the two handles are applied at the proper moment in the proper position. As soon as the handles have been firmly attached to the bag, the gripper 74 releases the same and the suction of the suction jets 75 is discontinued, thereby allowing the bags with the handle to pass on to the rack 81 where the bags are stored.

The bags are advanced and kept in the requisite position by the upper pair and the lower pair of conveyor belts 82 and 83, respectively, FIGURE 13 showing only one of each pair. The two belts of each pair come into contact with the bags at either side of the portion where the handles are to be attached. The bags are supplied to the conveyor belts at the proper predetermined intervals by conveyor belt 84, having bars 85 taking along the bags. The conveyor system moves at a somewhat slower speed than the transport belts 82 and 83. The two advancing rolls 87 and 86, roll 86 having a segment-shaped cross section, grasp the bags supplied by the conveyor system 84 and 85, bring them up to the higher speed of the transport belts 82, 83, and feed the bags to the latter. Due to the accelerated speed of the rolls 86, 87, the bags are safely taken over from the bars 85 before the same are moved to the lower side of the conveyor system 84. The bags are then passed between the cylinders 73, 80, each of which applies a handle to the bag whereupon the finished bags are passed onto the rack 81.

Operation of the Bast Containing Handle Embodiment of the Machine

The strip of material, for example the paper strip 122, is pulled off the feed roll 123. Simultaneously therewith, a strip of bast 124 is pulled off the feed roll 125. The paper strip is guided over the rods 126 and 127, between the adjustable lateral guide rings 128 and 129, as shown in FIGURE 33. From the rod 126 to the rod 127 the strip is advanced over the roll 130 and then to the glue-applying means, comprising the glue vessel 134 and the disks 135, 137, 138 and counter roll 131. In these glue-applying means the strip receives an uninterrupted central longitudinal strip of glue and two lateral interrupted longitudinal side strips of glue 132 and 133. These glue portions are applied by guiding the paper strip over the counter roll 131. Within the glue vessel 134 there rotate a central glue-applying disc 135 and before as well as behind the same the glue-applying discs 137 and 138

which are partly interrupted as at 136. After having applied the glue portions the paper strip 122 is united with the strip of bast 124. For this purpose, the strip of bast is guided over the guide rod 140 provided with the adjustable lateral guide rings 141 and 142. Due to these guide rings, the strip of bast is united with the paper strip as at 139 exactly in the central portion of the latter bearing the central longitudinal uninterrupted strip of glue.

10 The united web, composed of the paper strip and the bast strip is then advanced to the cutting means 143 comprising the fixed knife 144 and the two rotating knives 146 and 147, mounted on the rotary body 145. The rotating knives 146 and 147 have a central recess 15 portion 148, as shown in FIGURE 33, so that the paper strip is cut at the two sides of the bast strip as at 149 and 150 only. The same effect can be achieved by providing the fixed knife with a recess portion.

The rotating knives 146 and 147 are irregularly spaced 20 on the circumference of the rotary body 145 in such a manner, that the cuts are alternatingly spaced with the longer and the shorter distances, respectively, from each other on the paper strip. The rotary body 145 is so positioned with respect to the glue-applying discs 137 and 138 25 that the cuts are produced at the beginning and at the end of the interrupted lateral longitudinal glue strips 132 and 133. The glue-applying discs perform one revolution during each full rotation of the knives; however, their circumferential speed is greater than the speed of 30 the knives as well as the speed of the web, due to the greater diameter of the glue-applying discs. For that reason the glue is well pressed against the paper.

The web which has now been provided with the lateral cuts 149 and 150 is then guided over a rod 151 with 35 adjustable lateral guide rings 152 and 153 and is then advanced to the device 154 which folds the lateral glued portions 132 and 133 of the paper strip and attaches the same to the bast strip. For that purpose, the web is guided underneath the shoe 155 having the same width 40 as the bast strip and advanced to rotating segment discs 156 and 157 disposed at either side of the shoe 155, so cooperating with the latter as to vertically fold upwardly the lateral portions 158 and 159 of the web which are provided with the glued strips 132 and 133 and which are separated from the remaining portion of the web by the cuts 149 and 150. Thereupon the lateral portion of the strip 158 is folded down upon the bast strip by means of the first folding bar 160. Thereupon, the lateral portion 159 is folded on top of the lateral portion 158 by means of the second folding bar 161, as shown at the extreme left end of FIGURE 33. The lengths of the segments 156 and 157 are so chosen that only the lateral portions provided with glue are folded, whereas the non-glued portions remain unfolded.

55 Thereafter, the strip which had thus been prepared is advanced by analogous means as shown with respect to the embodiment of FIGURES 12 through 14, and is cut so as to obtain individual portions of the required lengths for one handle. The individual portions are cut 60 by the transverse cut in the middle of the non-folded strip portion 160a and along the dash-dotted lines 161-162a. Thus, the strip portions are provided with a portion to be glued at either side, that is portions 163 and 164, as shown in FIGURE 35, whereas the portion in-between, that is the portion 165, is folded around the bast strip and glued therewith.

The separated strips, each having the required length for a handle, are then advanced to a plate 166 as shown 65 in FIGURE 34 where they are conveyed to the cylinder 58 by means of needles 48 and 50, as described with respect to the basic embodiment, supra, and schematically illustrated again in FIGURE 34. The needles are inserted into the non-folded portions 163 and 164. After 70 having reached the cylinder 58 the strips are grasped by grippers 59 and 60, respectively.

The grooves in the strip are produced by the two grooving tools 167 and 168, cooperating with corresponding grooves 170 and 171 within the cylinder 58 instead of the folding knife of the basic embodiment described further above. Thus, two diagonal grooves 172 and 173 within the strip are produced, which grooves are inclined with respect to the longitudinal axis of the strips by an angle of 45 degrees.

Thereafter, the strips are further carried on by the cylinder 58, and the portions of the strip situated outside the diagonal grooves 172, 173, are pulled over fixed plates 174 and 175, and are thereby folded upwardly about the diagonal grooves. The end portions 163 and 164 are then pulled over the enlarged portions 176 and 177 of the plates 174 and 175, and are thereby brought between the flanges of the plates 174 and 175 and the two interior guide plates 178 and 179. (Compare also the dash-dotted lines in FIGURE 35.)

The strips are then pressed against the suction nozzles 181, 182, respectively, provided in the cylinder 58, by means of the plate 180, whereupon the strips are conveyed to the turning and gluing cylinder 73.

The strips are then processed in a manner and by means described with respect to the basic embodiment further above.

The Preferred Embodiment of the Machine

According to another, preferred embodiment of the apparatus of the invention, the groove applying elements 31, 32 as well as the members 25, 26 for producing a smooth surface portion on the strips of material, can be dispensed with. Furthermore, the advancing rolls 35, 36, the central pin 49 and the pairs of rolls 41, 42 and 43, 44 are replaced by a pair of belts, as will be explained presently. The preferred embodiment is further characterized by certain changes of the folding elements 65 through 70, and in that the folding cylinder is equipped with air suction means, and in that provision is made for automatic means for applying the bags to be equipped with the handles.

This preferred embodiment of the machine according to the invention will now be described in detail by referring first to FIGURES 15a, 15b through 28 of the drawings.

The Handle Strip Producing Mechanism of the Preferred Embodiment

The strip of material 23, for example paper, is stored on the feed roll 24, which latter is mounted upon a bushing 186 by means of the discs 183, 184, and an adjusting ring 185 positioned upon the disc 184. A knurl screw 187 is revolvably positioned in a cover 188 which is screwed upon the bushing 186. The knurl screw is thus prevented from lateral displacement while being capable of rotary motion. The knurl screw 187 is screwed into a stationary bolt 189, which is disposed in another bushing 190, the latter being, in turn, mounted within the bushing 186. By means of the screw ring 187 the bushing 186 can thus be displaced in axial direction along the stationary bolt 189.

A braking belt 191 is attached with one end to a fixed bolt 192a screwed into the machine frame. The braking belt is partly coiled about the feed roll 24 and connected with its other end to a weight 192 so as to be tensioned and exercise a braking effect upon the feed roll 24.

Next to the feed roll the machine comprises a guide bolt 193 bearing lateral, adjustable guide rings 194 and 195 for guiding the strip of material. After the bolt 193, there are provided deviating guide rolls 196, 197, 198, and, thereafter, a bolt 199 also having lateral, adjustable guide rings just as the guide bolt 193, for guiding the strip of material between them. Each of the deviating guide rolls 196, 197, 198 consists of a bushing 196c which is rotatably mounted on a bolt 196b screwed into the machine frame by means of ball bearings 196a,

as shown with respect to the deviating roll 196 in FIGURE 18.

The glue-applying means of the machine comprise the glue-applying counter roller 29, the glue-applying discs 28 and the glue vessel 27, which will next be described in detail.

The glue-applying counter roller 29 is equipped with means for lifting the same, shown in detail in FIGURE 19. The roller is mounted on a bolt 200, positioned on ball bearings 201, 202 in a hollow lever 203. The lever 203 is tiltably positioned upon a bolt 204 which has been screwed into the machine frame. A hand lever 205 is rotatably positioned upon a bolt 206 attached to the machine frame. A cam disc 207 is positioned on the hub of hand lever 205. A flat iron 208 is screwed into lever 203. By actuating hand lever 205 the lever 203 can be lifted or lowered and, hence, the roller 29 is also lifted or lowered accordingly. Furthermore, provision is made for a knurl ring 209 in the flat iron 208, whose lowermost tip comes to rest upon the cam 207. Thus, the resting position of lever 203 and, hence, the glue-applying counter roller 29 can be adjusted by turning the knurl screw 209.

The roll 29 is resiliently pulled in downward direction by a spring (not shown) attached to the spring bolt 210 screwed into the lever 203.

The roll 29 is driven by a gear 211, which gear is mounted on the bolt 200 and meshes with another gear mounted upon bolt 215. This latter gear and bolt 215 form part of the other elements of the glue-applying unit which will next be described.

The glue-applying discs 28 are mounted on a bolt 215 positioned below the roll 29. A flange bearing 212 is screwed against the machine frame and the bolt 215 is rotatably positioned on ball bearings 213, 214 in flange bearing 212. A gear 216 is mounted on bolt 215, whereas a gear 238 is mounted upon the shaft of the advancing roll 22. The two gears are connected via intermediate gears 310, 311, and the gear 238 thus drives the gear 216 and, hence, the bolt 215 bearing the glue-applying discs 28. These discs partly project into the interior of the glue vessel 27 and rotate therein. The glue vessel 27 is hingedly mounted on two levers 217, 218, which are rotatably positioned on fixed bolts 219, 220. Consequently, the glue vessel can be displaced about bolts 219, 220 so as to be removed from the glue-applying discs 28.

Close to the glue vessel 27 there is disposed a stop member 221, against which the vessel comes to rest in its working position. On either side of the glue-applying discs there are provided bars 222 and 223 to keep the side surfaces of the glue-discs free from glue. These lateral bars 222 and 223 are mounted on a bolt 226, the latter being screwed into the frame 225, by means of a knurl ring 224 and can thus be easily removed. Furthermore, the bolt 226 supports a third bar 227 extending transversely in regard to the glue-applying discs and above the respective peripheries of the same, as illustrated in FIGURE 20. The bar 227 has longitudinal slots 228.

Next to the roll 29, the machine has a guide roll 230 having lateral guide margins 231 (see FIGURE 21), and positioned in a like manner as the deviating rolls 196, 197, 198, i.e. it is rotatably positioned on ball bearings on a bolt attached to the machine frame. After the guide roll 230 there is provided a shoe 30 having the same width as the handle. The shoe 30 is screwed against the machine frame, as shown in FIGURES 15a and 21. Furthermore, a guide bolt 232 is also screwed to the machine frame.

The shoe 30 and the guide bolt effect a folding of the paper strip as described further below.

The machine further comprises the advancing means 21, 22, shown in detail in FIGURE 22, whose construction is generally known in the art and therefore need not

be described in detail. Suffice it to say that the upper advancing roll 21 is positioned in a lever 233, which, in turn, is mounted on a bolt 234 fastened to the machine frame, and which can be swivelled. The roll 21 is also provided with a hand lever 235 connected with a cam disc 235a, an adjusting screw 236, and a further lever 237 connected with lever 233, and the upper advancing roll 21 can thus be swivelled in an entirely analogous manner as the roll 29 (see further above). The advancing rolls 21 and 22 are connected with each other by means of gears 238 and 239 and are driven through an intermediate gear 240 which, in turn, is impelled through the further intermediate gear 241.

The cutting means 33, 34 of this preferred embodiment of the machine according to the invention is shown in detail in FIGURE 23. The lower knife 242 is mounted on block 34 which latter is screwed to the machine frame, whereas the upper knife 243 is screwed to a body 33, which latter is clamped upon a shaft 244 by means of the screw 245. The shaft 244 bears a gear 246 meshing with the intermediate gear 241 and transferring the driving motion to knife 243. Gear 241 is driven by gear 247, which is fixedly connected with gear 248 and rotatably positioned on a bolt attached to the machine frame. The gear 248 meshes with a further gear 249, as shown in FIGURE 15b.

Next to the cutting means 33, 34, the machine comprises further advancing means 37, 38 consisting of the lower advancing roll 38 and, peripherally adjacent thereto, a disc 37 with segment members 252 screwed against the disc 37 at either flat side of the latter. The disc 37 is positioned on a shaft 253, the latter being positioned in a lever 254. The lever 254 is positioned on a bolt 255 screwed to the machine frame, and can be swivelled. The lever 254 can be finely adjusted by the knurl screw 256 via the lever 258 connected with lever 254. The disc 37 and the roll 38 are provided with a recess 260, adapted to receive an upper and a lower belt 250, 251, respectively. The disc 37 is driven through gear 249 via the gear 259 mounted on shaft 253. Through the disc 37 the upper and the lower belt 250, 251, respectively, are driven. Associated with the upper belt there are provided a roll 45 and, between the latter and disc 47, a guide roll 39 and a pair of tension pulleys 261, 262. Associated with the lower belt is a roll 263 and, between the latter and disc 37 and roll 38, a pair of guide pulleys 264, 265 and two further rolls 266, 267.

The upper belt moves from disc 37 to the roll 45 and back to the disc 37, via the roll 39 and the pair of guide pulleys 261, 262. The lower belt moves towards the deviating roll 263 and back to the lower advancing roll 38, via the pair of guide pulleys 264, 265 and the two rolls 266, 267.

The machine is further equipped with guide means for the handle strips, as shown in FIGURE 28, and consisting of a base plate 295, upon which there are laterally mounted rails 296 and 297 reaching over the strip from both sides of the latter so that there is sufficient space for guiding the upper belt 250. The guide means with the base plate and the rails is attached to the machine frame 225 by means of angle irons 298. The guide rails are interrupted at the location of the advancing means 37, 38. The rail 297 only is remaining within the range of the rolls 39 and 45, so that it is possible to remove the strip by means of needles which have been omitted in FIGURE 15b for the sake of clarity.

There is also provided a stop member 47 adapted for arresting the movement of the paper strips by pressing the strip to the left and to the right of upper belt 250 on a table sheet 268. At this location the guide rails 296 and 297 are again interrupted. The stop member 47 is attached to an angular lever 269, 270, fulcrumed as at 271. At the lower end of lever arm 270 there is hingedly mounted a flat iron 273 having a fork-shaped end portion 272. (See also FIGURE 27.) The fork-shaped end

portion 272 is slid over a recess 274 so as to permit of horizontal, reciprocating movement of the flat iron 273 but keeping the same from falling. A pulley 275 is rotatably mounted on the flat iron 273. The pulley runs along a curved disc 276, it being pressed against the latter by conventional spring means (not shown). The curved disc 176 is mounted on a shaft 277 which latter is driven by gear 249 via gear 278 at the requisite speed and the proper interval so as to arrest the strip at the requisite location.

The table sheet 268 has bulged elongated portions 281 and 282 with slots 279 and 280 provided therein, through which the transferring needles are allowed to pass.

It is further necessary to provide for means allowing for removing the handle strip from between the belts 250, 251, by the two needles 48 and 50 (to be described presently; see FIGURES 29b and 30b), and transferring the strip to a processing cylinder, such as cylinder 58 in the afore-described basic embodiment, which was, however, omitted in FIGURE 15b for the sake of clarity. Provision is therefore made for means for lifting the upper belt 250, which will now be described. The rolls 45 and 39 are rotatably positioned on angular levers 283 and 284, which are, in turn, fulcrumed as at 285 and 286, respectively. The angular levers 283 and 284 are connected 25 with each other by rod 287 which can be elongated or shortened by turning the knurl screw 287a. The elongated arm of the angular lever 283 is hingedly connected with a lever 290 fulcrumed at 289, via a further rod 288, which can also be elongated or shortened, by turning the knurl screw 288a. A roll 291 is rotatably mounted on the lever 290 and runs along the curved rim of a disc 292 (see also FIGURE 30b).

A tension spring (not shown) presses roll 291 against the curved rim of disc 292. The disc 292 is mounted 35 rotatably on the shaft 293 and is impelled by the common driving means of the machine via gear 294.

The disc 292 thus rotates at the speed and with the intervals set by the machine and its driving means, and lifts the rolls 45 and 39 at the requisite moment, via the 40 curved disc 292, the roll 291, the lever 290, the rod 288, the angular lever 283, or the rod 287, the angular lever 284, respectively.

The Handle Strip Transfer Mechanism of the Preferred Embodiment

Turning now to the two transferring needles 48 and 50, referred to above, the same are shown in FIGURES 29b and 30b in the position in which they pierce the handle strip in order to transfer the same. For this piercing motion, the following structure is provided. The needles 48 and 50 are mounted on the levers 51, which latter are mounted on shaft 55. The shaft 55 also bears a lever 54 with a roll 53, running along the edge of disc 52. As shown in FIGURE 15b, the curved disc 52 is connected 55 with disc 292 and rotates together with the latter. The configuration of curve 52 is so adapted, that the insertion of the needles 48, 50 into the strip and their removal from the same is effected at the required moment, taking into consideration the time used for one reciprocation 60 of levers 56.

FIGURE 30b shows the drive for the reciprocating movement of lever 56. The drive is attached to the outside of the machine frame. The shaft 293 bearing the levers 56 projects from the frame. A lever 299 is clamped to the projecting portion of the shaft 293 and is hingedly connected with a link 300, the latter again being hingedly connected with a lever 301. The lever 301 is fulcrumed at 302 and supports a roll 303 running in a curved disc 304. The curved disc 304 is mounted on the portion of the holding knife shaft 305 projecting from the frame. The curved disc 304 can be displaced in longitudinal slots 306 and rotates at the rhythm of the machine. Thereby, the required swivelling motion is imparted by the curved disc 304 via the lever connection 300, 299, to the shaft 293 and hence to the lever 56.

The drive for the curved disc 292 and the curved disc 52 is also shown in FIGURES 29b and 30b, and comprises the gear 307 mounted on the folding knife shaft 305, the intermediate gears 308 and 309, and the gear 294 rotatably positioned upon shaft 293. Gear 294 is driven by gear 307 via the intermediate gears 308 and 309.

The Handle Forming and Applying Mechanism of the Preferred Embodiment

The machine is further equipped with gripping means, comprising the grippers 59 and 60, which will next be described, and which make it possible for the grippers to execute two different modes of operation, one being a gripping and releasing motion, the other being a movement along the circumference of the folding cylinder 58.

The gripper, e.g. the gripper 59, is mounted on the shaft 312 which is rotatably positioned in levers 313. The levers 313 are rotatably positioned on the folding cylinder 58 and fulcrumed at 314. A lever 315 is attached to shaft 312 and a roll 316 is rotatably positioned on lever 315. Associated with the roll 316 there is provided a curved member 317. A spring bolt 318 is connected with shaft 312 via an adjusting ring and is actuated by a tension spring 319, thereby pressing roll 316 against the curved member 317. The curved member 317 raises and lowers the roll 316 during its revolution with the folding cylinder 58, thereby causing gripper 59 to perform a gripping and releasing motion.

The grippers are further provided with means causing a movement about the circumference of folding cylinder 58. The shaft 314 supports a lever 320, the latter bearing a rotatably positioned roll 321. Associated with roll 321 there is provided a curved member 322. To lever 313 there is connected a tension spring 323, whereby roll 321 is pressed against the curved rim of curved member 322. The roll travels along curved member 322 and imparts a swivelling motion to gripper 59 via the lever 320, the shaft 314 and the lever 313.

The strip must then be folded in its grip portion. To effect this, the machine is equipped with a folding clamp 61 and a folding blade 64 (see also FIGURE 31). The folding clamp 61 is mounted upon a shaft 324, which latter is rotatably positioned in the folding cylinder 58. The shaft 324 further bears a lever 325 supporting at one of its ends a rotatably positioned roll 326. In addition, there is provided, in association with roll 326, a fixed curved member 327. A tension spring 328 is affixed to lever 325 and keeps roll 326 constantly pressed against the curved member 327. The required opening and closing motion of clamp 61 is imparted to the same by the curved member 327 and roll 326 travelling along the curved rim of the latter, via lever 325 and shaft 324.

The folding cylinder 58 is provided with conventional stop members (not shown) which prevent the tension springs from pulling down 317, 322, 327, the respective rolls associated with the curved members further than the lowest point of the effective curved rims of the curved members.

The machine is further equipped with means for applying the corner folds to the handle strips 438. They comprise the fixed sheets 439 and 440 (see FIGURES 29b and 31). Between these two sheets there are arranged two further fixed sheets 441 and 442 which latter are disposed at the distance from one another which is equal to the width of the handle strips 438. Two further sheets 443 and 444 are rotatably positioned upon bolts 445 disposed between the fixed sheets. Pressure springs 446 resiliently press the sheets 443 and 444 against the surface of cylinder 58. These springs 446 are connected to flat irons 447 disposed between the fixed sheets. A sliding bolt 448 is connected with the sheets 443 and 444 and has a head portion 448a. The bolt 448a slides in the flat iron 447. The head portion 448a thus prevents the sheets 443 and 444 from entering the intervals between the cylinder segments 58a and 58b of cylinder 58: the head 75

448 of bolt 448a comes to rest against the flat irons 447 and thus prevents the sheets 443 and 444 from moving in the direction towards the cylinder 58 too far.

After having been folded by the aforescribed means and in a manner to be described in detail further below, the handle strips are to be kept in the required position on the cylinder 58. Therefore, the cylinder segments 58a and 58b of the cylinder 58 are provided with suction nozzles 449. A central boring 451 communicates the suction nozzles 449 via borings 452 with a vacuum pump (not shown).

The machine is then further equipped with transferring and further glue-applying means which will next be described.

15 A transferring cylinder 73 is disposed close to the cylinder 58. This cylinder 73 has grippers 74 adapted to enter the interstices 450 of the gripper 59 (see FIGURE 31). The cylinder 73 is also provided with suction nozzles 75 communicating with a boring 454, and a central boring 453 communicating with a vacuum pump (not shown).
20 Associated with the transferring cylinder 73 there are provided further glue-applying means 76, 77, 79. The glue-applying segments 79 are mounted upon the shaft 455 rotatably positioned in the machine frame. The transferring cylinder 73 is driven by the driving gear 503 of cylinder 53.
25 The glue-applying segments 79 are driven by the driving gear 457 of the transferring cylinder, via a gear 456. The glue-applying discs 77 are mounted in bearings 458 rotatably on shaft 459, the bearings being fixed to glue vessel 76. The shaft 459 runs in flanges 460. The latter are inserted in slots 460a in the bearings 458.

30 The flanges have a lateral, longitudinal slot 461 and can be swivelled behind a wing screw 462 and can be fastened by the same, the wing being screwed into the bearings 458. Thus, the glue-applying discs 77 can easily be removed e.g. for cleaning purposes. Adjacent to the discs there is disposed a bar 463 which keeps the sides of the discs 77 free from glue. They can be adjusted by the knurl screws 464 disposed to the left and to the right of glue vessel 76.
35 It is thus possible to adjust the thickness of the film of glue on the discs.

40 A bolt 465 is fixed in a portion 466 of glue vessel 76. The bolt rests in longitudinal slots 467 at either side of the machine frame. It supports the glue vessel but, at the same time, allows for longitudinal displacements of the same.

45 For effecting the latter the following structure is provided. Screws 469 are fixed to the machine frame. The glue vessel has flat irons 471 at either side, the flat irons having rounded portions adapted to fit into grooves 470 of knurl nuts 468, which are screwed upon the screws 469 at either side of the glue vessel 76. By turning these knurl nuts 468, the glue vessel can be displaced longitudinally. This longitudinal displacement is necessary in order to adjust the amount of glue applied to the glue segments 79.

50 Furthermore, there are drive transmitting means transmitting the drive from the gear 456 of the glue segments to the glue-applying discs 77, and consisting of a gear not shown in the drawings which will be mounted upon shaft 459 of the glue-applying discs 77.

55 Finally, the transferring cylinder 73 has removing members 472 disposed between the grippers 74 and which serve the purpose of removing the handle grip portions from the grippers 74.

60 The machine has a lower transferring cylinder 80 whose structure and accompanying members correspond exactly to those of the upper transferring cylinder 73 with the following exception. The removing members associated with the lower cylinder 80 which are designated by number 476 and which correspond to the number 472 associated with the upper transferring cylinder 73 are so adapted that they project into the area defined by the narrow angle between the surface of the lower transferring cylinder 80 and the table sheet 496. This guarantees that the handle strip will not be transferred below the table sheet 496 but upon the same. Furthermore, the lower

transferring cylinder 80 differs from the upper transferring cylinder 73 in that the latter is really but a cylinder segment in order to allow for the passage of the thicker bottoms of the bags between the two cylinders 73 and 80. In contrast therewith, the transferring cylinder 80 is a full cylinder so that the bags have an uninterrupted support at the cylinder surface. Apart from these differences the structure is substantially the same in that the lower transferring cylinder 80 also has two grippers 473, suction nozzles 474 with a central boring 475. The lower folding cylinder 425 is also substantially the same as the upper cylinder 58 and, therefore, has not been reproduced in detail.

There is, however, a difference between the lower and the upper glue-applying means which is due to the fact that there is more space available for the lower glue-applying means. It would, therefore, be briefly described. A bolt 477 is attached with one end to the machine frame. The bolt supports a console 478 and upon which latter rests the glue vessel 505 in a U-shaped support 479. The U-shaped support has two screw bolts 480 upon which there are screwed the knurl nuts 481 with a groove 482. This groove receives a flat iron 483 attached to the console 478 and having a half-moon shaped recess. The glue vessel can thus be displaced in the direction towards the glue segments 484. The glue-removing bars 485 for the glue discs 486 are positioned in the same manner as the glue discs 77, and can be adjusted by knurl screws 487.

The Bag Conveying Mechanism of the Preferred Embodiment

The machine is further equipped with automatic bag applying means. There are provided sheets 352 limiting the bags 350 to the left and to the right (see FIGURES 29a and 30c). There is also provided a spindle 352a provided with a wheel 352b with a handle 352c. By means of these spindles the guide sheets 352 can be displaced in order to be adjusted to varying widths of the bags. Furthermore, there is a plate 353 having an angle member 354.

The automatic bag applying means further comprise air conveying means. Flange bearings 355 are at either side screwed to the machine frame. In the bearings, there are positioned shaft stubs 356 melded together with a flat iron 357. Suction members 358 are fixed to the flat iron 357 and are connected by hose pipes 359 to a conventional vacuum distribution system (not shown), the latter being connected to a vacuum, for example via a control valve 360, a cock 361 and a hose pipe 362. The control valve 360 houses a reciprocating bolt 363 which has a through-passing boring 369 and an angularly disposed boring 371. The control valve 360 has borings 369 and 370. The bolt 363 is hingedly connected with a link 364 as at 335. The link 364 is hingedly connected to one end of a lever 366, the other end of the latter being hingedly positioned as at 365. The lever 366 bears a roll 367 travelling along the curved rim of a rotating disc 368 while being constantly pressed thereagainst by a tension spring not shown.

A reciprocating movement is thus imparted to the bolt 363, as transferred from the disc 368 via the roll 367, lever 366, and link 364. During this reciprocating motion, the bolt naturally assumes two different end positions. In one end position vacuum is created in the hose pipes 359 via boring 369. In the other end position the hose pipes 359 communicate with the atmosphere via the borings 370, 371, thereby abruptly terminating the suction effect of the suction members 358.

There are further provided means for imparting a swivelling motion to the suction members 358, as shown in FIGURE 30c. A lever 372 is attached to one shaft stub 356. One end of lever 372 is hingedly connected with one end of the two-armed lever 375, 376, via a link member 373. The two-armed lever 375, 376 is positioned at 374 and its arm 376 bears a roll 377 associated with

a rotating curved disc 379, it being constantly pressed against the curved rim of disc 379 by means of a tension spring 378. A swivelling motion is imparted to the suction members 358 by the curved disc 379 and roll 377 via lever 375, 376, link 373 and lever 372.

There can be provided two or three suction members 358, depending on the width of the bags to be handled.

Associated with the suction members 358, and still forming part of the automatic bag conveying unit in the machine of the invention there are provided gripper means. The gripper means comprise grippers 380 disposed on rotating discs 381. There are a total of two rotating discs 381 bearing gripper members 380 and each flanked by a disc without grippers. In these latter discs there are positioned the gripper shafts 382.

The opening and closing operation of the grippers is performed by the following elements.

The discs 381 bear bolts 386 in which there are positioned two levers 385. A roll 387 is rotatably positioned on each of the two levers 385. A curved disc 384 is associated with the rolls 387, the latter being pressed against the curved rim of curved disc 384 by tension springs 388 and travelling along the same. At their respective free ends the levers 385 have a toothed segment 389, meshing with a pair of gears 383, the latter mounted on the gripper shafts 382. An up- and downward movement is imparted to the levers 385 by the roll 387 and the curved disc 384. The movement of the levers is transferred to the grippers via the toothed segment 389, the gear 383 and the gripper shafts 382, so as to open and close the grippers 380.

Furthermore, there are provided removing members 390 for removing the bags from the opened grippers.

Next to the grippers the automatic bag-applying unit 35 has a chain conveyor system 84, 85. It consists of two chains 84 running over two chain wheels 392, 393 rotatably positioned in the machine frame. The shaft 392a of the chain wheels 393 can be adjusted by a nut 394 in a slot 394a, so as to tension the chains. A driving gear 395 is mounted upon shaft 392a, which drives the chains. On each of the chains 84 there are screwed three push bars 85 being positioned adjacent to each other in pairs. Over the chains there are disposed two angular rails 396 supporting the bags transported by the chains on their respective left and right ends. The rails are slidably positioned on bolts 397 and can thus be adjusted to varying widths of bags.

There are further provided accelerated advancing means for advancing and accelerating the bags in order to prevent their being damaged by the push bars 85 whenever the latter travel about the chain wheel 395 to the lower side of the chain conveying system.

The upper, segment-shaped advancing roll 86 is positioned on a shaft which, in turn, is positioned in levers 399. These levers are rotatably positioned upon a bolt 400 attached to the machine frame. At their respective front ends the levers 399 bear a tension spring 332. The levers 399 further bear an adjusting screw 333 whose lower end comes to rest upon an anvil 334 mounted in the machine frame. Below the upper advancing roll 86 there is disposed the lower advancing roll 87.

The upper roll 86 has a recess 398, so as to be segment-shaped, which is necessary in order to accurately seize and convey the bags into the handle-applying units. The tension spring 332 resiliently presses the upper advancing roll 86 against the lower advancing roll 87. The adjusting screw 333, resting against the anvil 334 prevents, however, the upper roll 86 from being pressed against the lower roll 87 in the position where the recess 398 faces the periphery of the lower roll.

Next to the advancing means 86, 87 there is provided a belt conveying unit, comprising the upper belts 82 and the lower belts 83, running at the same speed as the advancing unit 86, 87. There are two upper belts 82 and two lower belts 83, as shown in FIGURE 31. The upper

belts 82 run over rolls 401, 402, their upper portions being guided below guide rolls 403 and 404, their lower portions being guided, together with the upper portions of the lower belts 83, over bent table sheets 405 and 406. The lower belts run over rolls 407, 408, their lower portions being guided over guide rolls 409 and 410. The rolls 401, 402, 407 and 408 and the lower advancing rolls 87 are mounted on shafts 411, 412, 413, 414, 415, the various shafts being positioned in the machine frame.

The driving means for the various aforesaid conveying and advancing means in the automatic bag-
applying unit are as follows: The shaft 413 bears a gear, not shown, whose pitch circle coincides with the circumference of the rolls 407. It is driven by the driving gear of the lower transferring cylinder 80, via the intermediate gears 416, 417, 418.

The aforementioned gear upon shaft 413 also drives the shaft 415 of the lower advancing rolls 87, via an intermediate gear 419.

There is provided a further intermediate gear 420 for driving the chain wheels 392: The gear upon shaft 415 drives this intermediate gear 420, and thereby the gear 395 upon the shaft of the chain wheels 392. Gear 330 is driven by gear 395 via the intermediate gear 331 (see FIGURE 30c). FIGURE 30b shows still a further gear 421 which is mounted on shaft 413 of the lower belt rolls 407, while still another gear 422 is mounted on the shaft 411 of the upper belt rolls 401. The shaft 411 and thereby the upper belt rolls 401 are driven by the gear 421 on the shaft of the lower belt rolls 407, via the gear 422.

The shaft 414 of the belt rolls 408 also bears a gear having the same pitch circle as the belt rolls, with which there are associated two intermediate gears 423 and 424. It is driven by the gear of the lower folding cylinder 425 via the intermediate gears 423, 424.

The shaft 412 of the belt rolls 402 of the upper belts 82 bears a gear 426, while the shaft 414 of the belt rolls 408 of the lower belts 83 bears a gear 427 having the same dimensions as gear 426. The shaft 412 and hence the upper belt rolls are accordingly driven by shaft 414 of the lower belt rolls via the gears 427 and 426.

The belt guide rolls 403, 404, 409 and 410 are mounted on bolts fastened to the machine frame rather than upon shafts, in order not to obstruct the central space of the machine where the handles are being applied to the bags. For the same reason the belts 82 and 83 are laterally disposed of the handles, as shown in FIGURE 31.

Next to the handle applying unit described further above, the machine of the invention comprises, as a continuation of the belt system 82, 83, another belt system 429, 430, consisting of the upper belt 429 running on two rolls, and the lower belt 430 also running on two rolls. The rolls for the belts 429, 430 are positioned just as the rolls for the belts 82, 83, and are driven by the shaft 414 via the gears 434, 435, 436. However, only one end of the belts 429, 430 is guided over impelled rolls, whereas the belts 82, 83 are guided at both of their respective ends over impelled rolls. A table sheet 428 is disposed between the two belt conveyor systems 429, 430, and 82, 83. Underneath the lower portion of the upper and the upper portion of the lower belt, there is arranged a slightly curved table plate 431.

After the last mentioned belt system, the machine is equipped with an angular shaped deposit 432, 433, whose legs 433 have a centrally cut-out portion allowing for passage of the handles therethrough (see FIGURE 31).

The various table sheets referred to further above, namely the sheets 405, 406, 428 and 431 are mounted on flat irons, e.g. 437, screwed to the machine frame.

The Power and Common Drive Mechanism of the Preferred Embodiment

Finally, the common driving means for driving the various units described heretofore consist of the follow-

ing structure, shown in FIGURES 30b and 31. The entire machine has a single motor 488 with a shaft 489. Upon the shaft 489 there is disposed a driving belt disc 490. Driving belts 491 run on this disc 490 and a further driving belt disc 492 disposed on a shaft 493 positioned in side frame 494 of the machine. Shaft 493 supports a gear 495 outside of frame 494 (see FIGURE 30b), and a smaller gear 496 inside of frame 494, the latter meshing with the driving gear 497 of the folding cylinder 425.

10 The greater gear 495 is in driving connection with two further gears 498, 499, which are also disposed outside of frame 494 (see also FIGURE 31). Gear 499 meshes with gear 500 mounted on a shaft 501 which latter is also positioned in frame 494 and bears a gear 502 inside of the frame, which gear is somewhat smaller than gear 500 disposed outside of the frame. The gear 502 meshes with the driving gear 503 of the upper folding cylinder 58.

The lower shaft 493 as well as the upper shaft 501 have outer elongated portions bearing a bevel gear 504, meshing with the bevel gear 335 upon shaft 336, thus driving the upper strip advancing system via gear 249. In an analogous manner the driving impulse for the lower strip-advancing system is derived from the lower shaft 493.

The lower cylinder 425 is thus driven by gear 497, 25 which is driven from the motor 488 via shaft 489, belt 491, disc 492, shaft 493 and gear 496.

The upper cylinder is driven from the motor 488 via shaft 489, belt 491, disc 492, shaft 493 and gear 495, gears 498 and 499, gear 500, shaft 501, gear 502 and the 30 driving gear of cylinder 58, designated by numeral 503.

Operation of the Preferred Embodiment of the Machine

The various units of the preferred embodiment of the machine which have just been described operate and 35 cooperate in the following manner:

The strip of material 23 is obtained from the feed roll 24. The strip can be laterally adjusted if necessary by means of the knurl screw 187 displacing the bushing 186 with the bushing 190 in axial direction upon the bolt 189 40 thereby displacing the feed roll 24 mounted on the bushing 186. A certain tension is applied to the strip when pulled off the feed roll by the breaking belt 191 tensioned by the weight 192.

From the feed roll 24 the strip 23 is first guided to 45 the guide bolt 193. It is laterally guided by the adjusting rings 194 and 195. From the bolt 193 the strip is guided over the deviating rolls 196, 197, and 198 up to a further bolt 199 upon which it is again laterally guided by two adjusting rings.

50 From the bolt 199 the strip 23 is guided to the glue roll 29. The glue roll is driven by the gear 211 on the bolt 200 meshing with the gear 216 upon the bolt 215. The glue roll 29 can be lifted by the hand lever 205 via the cam disc 207, the lever 203 and the bolt 200 bearing 55 the glue roll 29.

The glue-applying discs 28 are driven by the gear 238 mounted upon the shaft of the advancing roll 22, via the intermediate gears 310, 311, and the gear 216 mounted upon the bolt 215 carrying the glue-applying 60 discs 28. The discs 28 which are thus driven rotate in the glue vessel 27. The amount of glue applied to the strip 23 can be adjusted by the member 227 through the longitudinal slots 228. The strip 23 is guided about the glue counter roll 29 and is provided with the glue strips 4 and 5 (see FIGURES 1 and 20). After the change 65 of direction of the strip 23, due to its having been guided about the glue counter roll 29, which new direction is indicated by the arrow 229 in FIGURE 20, the glue strips 4 and 5 are now on the upper side of the 70 strip.

From the glue counter roll 29 the strip 23 is led to the guide roll 230 and from there it is passed under the shoe 30. The shoe has the width of the handle to be produced, and the lateral portions of the strip 23 projecting at either side of the shoe are folded upwardly.

From the shoe 30 the strip is guided over a bolt 232 causing the lateral portions of the strip to become adjacent to its central portion so as to be glued thereto by the glue strips 4 and 5.

Thereafter the handle strip reaches the advancing means 21, 22. The advancing rolls 21 and 22 are driven via the intermediate gears 240, 241, and the gears 238, 239. The strip is thus further advanced by these rolls to the cutting units 33, 34. The upper knife 243 which is mounted on the body 33 positioned on shaft 244 is driven by the gear 249 via the gear 248, the gear 247, the intermediate gear 241, and the gear 246, which latter is mounted on the shaft 244. Thereby the strip 23 is cut by the moving knife 243 performing the cutting operation at predetermined intervals, thus cutting predetermined lengths of strips.

At the moment where it is cut, the cut-off portion of the strip is grasped by the advancing units 37, 38. The disc 37 with the segment pieces 252 and the roll 38 rotate at a higher speed and impart to the strip a greater speed than the speed with which it travelled so far. The two belts 250 and 251 also move at this accelerated speed. Before the strip has been grasped and brought to the higher speed it moves slower than the belts 250 and 251 so that the latter slip over the strip, thereby tightening it. After the strip has been brought to the accelerated speed it maintains this speed when travelling along the belt 250 and 251. Consequently, the separated strips finally attain a certain distance a between the individual strip sections (see FIGURE 31).

During the travel, the strips are guided by the base plate 295 and the two lateral rails 296 and 297.

The movement of the strip with the belts 250 and 251 is halted by the stop member 47 pressing the strip upon the table sheet 268 to the right and to the left of the upper belt 250, while the belts continue to move and slip over the arrested strip. The stop member is actuated in the rhythm of the machine, by the gear 249 via the gear 278 upon the shaft 277, the curved disc 276 upon which runs the roll 275 mounted upon the flat iron 273, the levers 270, 269, which latter bears the stop member 47. Since the stop member is actuated in the rhythm of the machine the strip will be arrested at the proper moment and the predetermined location.

The strip is thereafter transferred to the cylinder 58 by the needles 48 and 50 in a manner to be described presently, vertically with respect to its previous direction of movement. In order to make this possible and to enable the strip to leave the two belts 250, 251, it is first necessary to lift the upper belt. This is done by the rolls 45 and 39 which are lifted at the predetermined moment. This movement is effected by the gear 294 driving the disc 292 upon the shaft 293 and further via roll 291 travelling along the curved rim of disc 292, the lever 290, rod 288, angular lever 283 and rod 287 and angular lever 284, respectively, the rolls 45 and 39 being mounted on the angular levers 283 and 284.

After the rolls have thus been lifted the two needles 48 and 50 pierce the strip which movement is imparted to the needles by the disc 292 rotating in the rhythm of the machine, connected with the curved disc 52 rotating therewith, the roll 53 travelling along the curved disc 52, the lever 54 mounted on the shaft 55, and the lever 51 supporting the needles 48 and 50. One machine rhythm covers the time used for piercing the strip, moving the strip to the cylinder 58, removing the needles from the strip and moving the needles to the next following strip in order to pierce the same. Accordingly, the curved disc 52 is so shaped that the needles pierce the strip and release the same at the proper moments.

After the needles have thus pierced the strip they move the same to the cylinder 58; the needles are moved by the reciprocating levers 56. The reciprocating levers are moved by the curved disc 394 cooperating with the

roll 303, the lever 301, link 300, lever 299, and shaft 293, bearing the levers 56. The curved disc rotates together with the folding knife shaft 305 in the rhythm of the machine.

After the strip has thus been transferred to the cylinder 58, it is first grasped by one of the grippers 59, 60, while the gripper is considerably further to the left from the position shown in FIGURE 29b. The grippers perform two different motions, a grasping and releasing motion, and a movement in circumferential direction with respect to the folding cylinder. The grasping and releasing of the gripper 59 is produced by the curved member 317 lifting and lowering the roll 316 running along its curved rim while travelling along with the cylinder 58, the movement of the roll 316 being transferred to the gripper 59 via the lever 315 and the shaft 312 bearing the gripper 59. The circumferential movement of the gripper 59 with respect to cylinder 58 is derived from the curved member 322 cooperating with roll 321, lever 320, shaft 314, lever 313 and shaft 312.

After the gripper 59 has grasped the handle strip at its right edge (FIGURE 29b), it is conveyed by the rotating movement of cylinder 58 underneath the folding knife 64. This knife folds the strip in its central portion into the opened folding clamp 61 (see also FIGURE 31). The necessary opening and closing movement of clamp 61 is obtained from the curved member 327 cooperating with the roll 326, via the lever 325 and the shaft 324 supporting the clamp 61.

At the very moment where the grip portion of the handle strip is folded by the action of folding knife 64 the gripper 59 is lifted and the strip is released. The handle strip now has the configuration as shown in FIGURE 31 and designated by the reference numeral 438. Thereupon, the clamp 61 is opened and the gripper 59 moves circumferentially with regard to cylinder 58 toward the erected double-folded grip portion of the handle strip and tilts the same contrary to the direction of movement of the folding cylinder, the folding clamp 61 opening at this moment. The edges 59a and 59b (see FIGURE 31) of the gripper 59 exactly reach the locations which will later on bear the folding lines extending rectangularly to the strip.

As the strip 438 continues to rotate with cylinder 58 its ends 65 and 66 laterally projecting from the cylinder meet the fixed sheets 439 and 440 (see FIGURES 29b and 31), where the ends are folded up so as to form an angle with the grip portion and whereby the corner folds are formed. The ends 65 and 66 are pulled toward the exterior sheets 439 and 440 and further fixed the interior sheets 441 and 442 so that they reach the sheets 443 and 444 exactly at the right angle. By the sheets 443 and 444 the ends are pressed against the cylinder surface as the sheets are resiliently pressed against that surface by the springs 446. Thereby, the corner folds of the handle strips are well applied and the ends 65 and 66 are brought closely to the suction nozzle 449 in the cylinder segments 58a and 58b. The ends of the strips are thus held against the cylinder in the necessary position. They then continue to move with the cylinder until they come close to the transferring cylinder 73. Here they are grasped by the grippers 24 of the transferring cylinder 73, the grippers reaching into the interstices 450 of the gripper 59 or 60 which has already released the strip and has somewhat receded from the same. The grippers 24 catch the strip at its grip portion (see also FIGURE 31), whereupon they are pressed against the cylinder surface by the suction effect of the suction nozzles 75. The transferring cylinder 73 passes the handle strip on to the glue-applying units 76, 77 and 79 where they receive the glued portions 19 and 20 from the glue-applying segments 79. The latter receiving glue from the glue-applying discs 77, the glue being obtained from the glue vessel 76.

The glue-applying segments 79 are driven by shaft 455

which, in turn, is impelled by the driving gear 503 of cylinder 58 via the driving gear 457 of the transferring cylinder 73 and the gear 456. The glue discs 77 are driven by the shaft 459 which is impelled by the gear 456 of the glue segments via a gear on shaft 459, not shown.

The handle strips which have thus been provided with glued portions at the sides which were the lower sides on cylinder 58 are thus advanced to meet the bags which latter are conveyed to the area between the transferring cylinders 73 and 80 at predetermined intervals in a manner described further below. As soon as the handles have reached the bags the grippers 74 open and the suction effect of the suction nozzles 75 is stopped so that the handles are released by cylinder 73. Their removal is further guaranteed by the bar elements 472 disposed between the grippers 74 and removing the grip portions of the handles from the grippers.

In an entirely analogous manner a second handle is applied to the lower side of the bags by the lower transferring cylinder 80.

The bags 350 are automatically conveyed at predetermined intervals to the transferring cylinders 73 and 80 for application of the handles in the following manner: The bags 350 are introduced into the automatic bag-applying unit with their respective bottoms 351. To the left and to the right they are confined by the sheets 352 which have previously been adjusted to the particular width of the bags by the handle 352c and the spindle 352a. The bottoms hit against the plate 353 and are supported by the angle 354 of the plate. The bags are then conveyed by the suction members 358 during which movement the bag is bent downwardly and pulled over the angle member 354 which safely prevents that more than one bag is conveyed at a time. The bag bottoms are then grasped by grippers 380. The opening and closing motion of the grippers is obtained from the curved disc 384 and the roll 387 running along the curved rim of the disc, via the bolt 386, the levers 385 with the toothed segment 389, the gear 383, and the gripper shafts 382. The grippers 380 convey the bags, with their respective bottoms coming first, up to the removing bar 390 which latter removes the bags from the grippers 380 which have opened in the meantime. The bags then fall on the chain conveyor system 84, 85 moving the bags in the direction of the arrow 391. The chains are driven over shaft 392a, the chain wheel 392 and the gear 395. The push bars 85 push the bags into the direction of the arrow 391 into the machine, with the respective open ends coming first. The bags are supported by the angular rails 396. The bags are then grasped and accelerated by the segment-shaped advancing roll 86 rotating together with the lower roll 87 at a higher speed. Thereby the bags are supplied to the handle-applying unit at the exact moment.

The bags are then passed to the belts 82 and 83 moving at the same speed as the rolls 86, 87. The belts grasp the bags on their respective sides and convey the same through the handle-applying unit in the direction of the arrows shown in FIGURE 31. During this passage the bags are conveyed over the slightly curved table sheets 465 and 406 and are provided with the handles by the cylinders 73, 80 as has been described further above. The bags which have thus received two handles are then pushed by the belts 82, 83 over the table sheet 428 to a further belt system 429, 430. They are then conveyed by the latter belt system over the slightly curved table plate 431, thus being subjected to sufficient pressure in order to firmly press the handles against the bags. Therefore, the bags fall upon the angular deposit 432, 433.

It will be understood that this invention is susceptible to modification in order to adapt it to different usages and conditions and, accordingly, it is desired to comprehend such modifications within this invention as may fall within the scope of the appended claims.

What we claim is:

1. A method for producing from paper and the like material and applying to bags handles therefor, the grip portion of which is double-folded and, with respect to the bag, inwardly and downwardly folded, comprising the steps of substantially continuously conveying the strip lengths of material, double-folding the grip portion of the strip lengths, folding the end portions of the strip lengths contrary to their direction of movement so as to 10 form an angle with the grip portion, turning the handles, and applying the same to bags with the side that is now upwardly turned.

2. A method for producing from paper and the like material and applying to bags handles therefor, the grip portion of which is double-folded and, with respect to the bag, inwardly and downwardly folded, comprising the steps of substantially continuously conveying a strip of material, folding the longitudinal side portions of the strip and gluing them upon the central portion so as to 20 reduce the width of the strip to half, cutting strip lengths from the strip, double-folding the grip portion of the strip lengths, folding the end portions of the strip lengths contrary to their direction of movement so as to form an angle with the grip portion, turning the handles, and applying the same to bags with the side that is now upwardly turned.

3. A method for producing from paper and the like material and applying to bags handles therefor, the grip portion of which is double-folded and, with respect to the bag, inwardly and downwardly folded, comprising the steps of substantially continuously conveying a strip of material, folding the longitudinal side portions of the strip and gluing them upon the central portion so as to 30 reduce the width of the strip to half, cutting strip lengths from the strip, double-folding the central portion of the strip length, applying corner folds to the strip lengths consisting of a pair of angular grooves in the folded side portions and a pair of short, transverse grooves starting from the point of the angular grooves in the center of the strip 35 length, folding the end portions of the strip lengths contrary to their direction of movement so as to form an angle with the grip portion, turning the handles, and applying the same to bags with the side that is now upwardly turned.

4. A method for producing from crepe paper and applying to bags handles therefor, the grip portion of which is double-folded and, with respect to the bag, inwardly and downwardly folded, comprising the steps of substantially continuously conveying the strip of material, cutting strip lengths from the strip, smoothening portions of the crepe paper to be applied to the bags in an intermittent operation, double folding the central portion of the strip lengths, folding the end portions of the strip lengths contrary to their direction of movement so as to 50 form an angle with the grip portion, turning the handles, and applying the same to bags with the side that is now upwardly turned.

5. A method for producing from paper and the like material and applying to bags handles therefor, comprising the steps of pulling an endless paper strip off a feed roll, bringing on to the paper strip an uninterrupted central glued portion and partially interrupted lateral glued portions, pulling a bast strip off a feed roll, uniting the bast strip and the paper strip so that the bast strip is glued 60 to the central portion of the paper strip, cutting the strip so that the cuts reach from both sides of the longitudinal edge to the bast strip and are disposed at the beginning and the end of the interrupted glued portions, folding side portions upon the bast strip, cutting off lengths of 65 the strip for the individual handle portions, pressing in the strip with two diagonal grooves and folding the end portions about the grooves so as to form an angle with the grip portion, and applying the handles to the bags.

6. Apparatus for producing from paper and the like material and applying to bags handles therefor of the

type comprising strip-preparing and strip-cutting means, handle-forming-and-applying means angularly disposed with respect to said strip-preparing and strip-cutting means, transferring means for transferring the strip of paper from said strip-preparing-and-cutting means to said handle-forming-and-applying means, and bag conveying means, said apparatus comprising, in combination, paper strip supplying means and bast band supplying means, glue applying means adapted to provide the paper strip with an uninterrupted central glued portion and lateral, partly interrupted glued portions, means for uniting the paper strip with the bast band, cutting means for producing lateral cuts in the paper strip reaching up to the bast band, intermittently operating folding means for folding the glued lateral portions of the strip upon the central portion, and groove applying means for producing diagonal grooves in the strip, and fixed guides for folding the strips about the diagonal grooves.

7. Apparatus as described in claim 6, said glue applying means comprising a glue vessel, a glue applying counter roll and two outer and one inner glue applying disks rotating in said glue vessel in front of said counter roll, said outer disks being segment shaped.

8. Apparatus as described in claim 6, said cutting means comprising a fixed knife, a rotary body and a plurality of knives irregularly spaced on said rotary body and having a central recessed blade portion.

9. Apparatus as described in claim 6, said cutting means comprising a fixed knife having a central recessed blade portion, and a rotary body and a plurality of knives irregularly spaced on said rotary body.

10. Apparatus as described in claim 6, said intermittently operating folding means comprising a shoe member, and, disposed at either side thereof, two segment discs, and, associated therewith, a pair of folding bars.

11. Apparatus as described in claim 6, with a working cylinder associated with said handle-forming-and-applying means and a transferring cylinder, said groove applying means comprising a pair of rotary grooving tools co-

operating with a pair of recesses in the surface of said working cylinder.

12. Apparatus as described in claim 6, comprising a pair of fixed folding bars associated with said folding means, said folding bars having enlarged surface portions, and guide sheets disposed between said folding bars, so as to guide and fold the end portions of the strip so as to form an angle with its central portion.
13. Apparatus for forming and applying to bag handles therefor from paper and the like material comprising, in combination, a handle strip preparing unit with means arranged in series in strip moving direction for continuous folding of the sides of a strip onto the center of the strip and for cutting individual handle lengths from the strip, and, operating in a direction normal to the operating direction of the handle strip preparing unit, means for forming and attaching handles, comprising a first cylinder with means for gripping the individual handle lengths and means for double-folding the grip part of the handle length and with means for folding the end portions angularly to the grip part and for folding the corner folds, and a second cylinder with gripping means for taking over the handle lengths from said first cylinder with upwardly directed underside and for transferring the handle lengths to the bags, and intermediate said handle strip preparing unit and said means for forming and attaching handle lengths a transferring means, said transferring means comprising a plurality of needles adapted for insertion into and removal from the strips, a plurality of reciprocating levers and a plurality of further reciprocating levers fulcrumed on said first levers and bearing said needles.
